UNITED STATES PATENT OFFICE.

NICHOLAS MARCALUS, OF PLAINFIELD, NEW JERSEY, ASSIGNOR TO NILES-BEMENT-POND COMPANY, OF NEW YORK, N. Y., A CORPORATION OF NEW JERSEY.

ADJUSTING AND CLAMPING GIB.

Application filed December 20, 1923. Serial No. 681,782.

To all whom it may concern:

Be it known that I, NICHOLAS MARCALUS, a citizen of the United States, residing at Plainfield, in the county of Union and State 5 of New Jersey, have invented certain new and useful Improvements in Adjusting and Clamping Gibs, of which the following is a specification.

This invention relates to gibs and particularly to a novel combined adjusting and clamping gib. In planers and like machine tools, wherein a tool saddle is slidably mounted on a supporting guideway, the saddle should be so mounted on the guideway that looseness and chatter thereof in operation is prevented. In ordinary practice, the saddle is fitted as accurately as possible to its guideway by adjusting gib. However, the positive preventing of looseness and chatter can only be accomplished by firmly clamping the saddle to its guideway. The primary object of my invention is the provision of a novel combined adjusting and clamping gib adapted to serve both 25 to accurately adjust the saddle to fit the guideway and to clamp the saddle rigidly thereto.

It will be understood that in planing operations, the tool supporting saddle must be given a feeding movement on the cross rail after each cutting operation. The saddle therefore must necessarily be unclamped to perform such feeding movement and, to assure perfect rigidity, should be clamped 35 thereafter prior to the cutting operation.

In the accompanying drawing, I have illustrated means for so operating the clamping gib mentioned above. This means is specifically shown and described in a co-pending application to Randolph et al. Serial No. 675,203, filed November 16, 1923.

With the above and other objects in view, my invention consists in the features of construction and operation set forth in the following specification and illustrated in the accompanying drawing. In such drawing annexed hereto and forming a part of this specification, I have shown one embodiment of my invention used in connection with a planer but it will be understood that the invention can be otherwise embodied and that the drawing is not to be construed as defining or limiting the scope 50 of the invention, the claims appended to this

specification being relied upon for that purpose.

Referring to the figures of the drawing: Figure 1 is a fragmentary plan view of a planer showing the use of my invention thereon.

Fig. 2 is a fragmentary front elevation thereof.

Fig. 3 is a perspective view of my novel combined adjusting and clamping gib.

Fig. 4 is a perspective view of the clamping portion of the gib.

Fig. 5 is a perspective view of the adjusting portion of the gib.

In the drawing, 1 indicates a pair of planer uprights on which a cross rail 2 is 70 adjustably mounted. The uprights are provided with inwardly projecting integral portions 3 secured together by bolts 4. The forward faces of these portions 3 are finished off at 5 to receive the cooperating face 75 of a rearwardly extending portion 6 of the cross rail, such portion 6 also preferably being integral with the rail. Bolts 7 in the portions 3 extend into T-slots 8 in the cross rail whereby the cross rail and uprights 80 can be securely clamped together at 5. The intermediate portion of the cross rail over the table is therefore rigidly backed up by the two uprights in a manner to securely hold the same against vibration during the 85 cutting operations. This construction comprises the subject matter of Patent No. 1,519,332 granted December 16, 1924.

A saddle 9 is slidably mounted on the rail 2 and supports a tool slide 10 vertically 90 adjustable therein. A taper gib 11 is adapted to accurately adjust the slide 10 in its guideway and a clamping gib 12 is provided for rigidly clamping the slide 95 therein. This mechanism and its operation are fully described in the above mentioned application, Serial No. 675,203. The saddle can likewise be accurately adjusted on the rail guideway and rigidly clamped thereto by means of my novel combined adjusting and clamping gib now to be specifically described.

My novel combined adjusting and clamping gib comprises two gib elements 13 and 14, the element 13 preferably being slotted at 15 to receive the element 14 therein. The element 13 is the adjusting portion of the gib and the element 14 is the clamping por-

tion thereof. These elements, assembled as shown in Fig. 3, are adapted to be inserted between the top guideway surface 16 of the cross rail 2 and the adjacent inclined bottom surface 17 of the saddle. The element 13 has a laterally projecting end 18 through which extends a screw 19 threaded into the saddle. By rotating the nuts 20 on this screw, the element 13 can be adjusted in the usual manner to accurately fit the saddle to the rail guideway.

The clamping gib element 14 has a notch 21 therein into which extends an arm 22 of a bell crank pivoted on the saddle at 23. The other arm 24 of the bell crank carries a pin 25 which engages in an inclined groove 26 in the forward face of a block 27. A shaft 28 anchored against axial movement in a bearing 29 on the saddle is screw threaded into the block. The shaft is splined for axial sliding movement within a driving sleeve 30. This connection between the sleeve and shaft permits adjustment of the saddle on the rail. It will be noted that as the sleeve 30 is rotated in one direction or the other, the block 27 will be moved along the threaded shaft 28 and slide the element 14 into and out of its saddle clamping position. The means for operating the sleeve in timed relation to the feeding of the saddle is fully disclosed in the above mentioned application Serial No. 675,203.

It will be noted that my novel combined adjusting and clamping gib is made in two parts and each part performs its function independently of the other part. Furthermore, the two parts, as shown in Fig. 3, are so constructed that combined they provide a gib of the usual configuration. It is believed that the construction and operation of my invention together with the advantages secured thereby will be readily appreciated without further description.

What I claim is:

1. A combined adjusting and clamping gib comprising two adjacent taper elements

for cooperating with two relatively movable members, one of the elements being movable for relatively adjusting the two members, and the other element being movable to clamp and unclamp the two members.

2. A combined adjusting and clamping gib comprising two adjacent equi-tapered elements for cooperating with cooperating guideway surfaces of two relatively movable members, one of the elements being movable for adjusting the two members and the other element being movable to clamp the two members.

3. A combined adjusting and clamping gib comprising two adjacent taper elements for cooperating with two relatively movable members, one of the elements being recessed and receiving the other element therein, and the elements having means whereby one can be moved for relatively adjusting the two members and the other can be moved to clamp and unclamp the two members.

4. A combined adjusting and clamping gib comprising two adjacent taper elements for cooperating with two relatively movable members, one of the elements being housed within a through slot cut in the other element and one element being movable for relatively adjusting the two members and the other element being movable to clamp and unclamp the two members.

5. A combined adjusting and clamping gib comprising two adjacent taper elements for cooperating with two relatively movable members, one element having a laterally extending projection whereby the same can be adjusted longitudinally for adjusting purposes and the other element being slidably mounted in a through slot in the said one element and having means whereby the same can be moved longitudinally therein for clamping purposes.

In testimony whereof, I hereto affix my signature.

NICHOLAS MARCALUS.
